United States Patent Office

Des. 202,581
Patented Oct. 19, 1965

202,581

REPRODUCTION MACHINE

Lewis Edward Simpson, 255 W. 234th St., Wilmington,
Calif., and William Eugene Karow, 7326 W. 93rd Place,
Los Angeles, Calif.

Filed Oct. 1, 1964, Ser. No. 81,966

Term of patent 14 years

(Cl. D61—1)

FIGURE 1 is a front perspective view of a reproduction machine, showing our new design;

FIGURE 2 is a rear perspective view of the reproduction machine of FIGURE 1, on a reduced scale; and

FIGURE 3 is side elevation view thereof, to a reduced scale, the opposite side of the machine being substantially a mirror image of this view.

The essential features of our design are shown in full lines.

We claim:

The ornamental design for a reproduction machine, substantially as shown and described.
